UNITED STATES PATENT OFFICE.

EDWIN S. WOODS, OF CHICAGO, ILLINOIS.

BRAKE-SHOE.

No. 885,414.

Specification of Letters Patent. Patented April 21, 1908.

Application filed August 14, 1907. Serial No. 388,437.

To all whom it may concern:

Be it known that I, EDWIN S. Woods, a citizen of the United States, and a resident of Chicago, in the county of Cook and State of Illinois, have invented certain new and useful Improvements in Brake-Shoes; and I do hereby declare that the following is a full, clear, and exact description thereof, reference being had to the accompanying drawings, and to the letters of reference marked thereon, which form a part of this specification:

The invention relates to improvements in brake-shoes designed for use in braking apparatus for railway cars, locomotives and the like, and the invention consists in the matters hereinafter set forth and more particularly pointed out in the appended claims.

My invention relates to an improved wearing or friction face for brake-shoes of this character, and also to a safety attachment designed to prevent parts of the shoe from falling away from the brake-head in case of fracture of the shoe when in use.

It has heretofore been proposed to increase the life and efficiency of brake-shoes by forming the wearing face thereof with alternate soft and hard metal areas, the latter areas having been provided either by incorporating metal inserts in the wearing face of the shoe, made of harder metal than that of the other parts of the wearing face, or by chilling separate areas of the friction face of the shoe in the mold during the casting operation. It is to the latter general type of brake-shoe to which my invention belongs.

The object of this feature of the invention is to produce a brake-shoe, the wearing face of which is composed of chilled and relatively soft areas so arranged with respect to each other that the proportions of the two areas of differently wearing metal will remain substantially uniform during the life of the shoe, thus producing a shoe having a substantially uniform efficiency throughout the greater portion of its life; to produce a shoe in which the relation of the chilled area to the depth or thickness of the shoe from front to back is such that said chilled area remains effective and efficient during the maximum life of the shoe, or until it is unsuitable for further use; to produce a shoe having the above mentioned properties wherein the chilled area or areas extend from margin to margin of the wearing face; and, lastly, to produce a shoe wherein the chilled areas are formed on the

sides and bottom walls of depressions of substantial depth in the face of the shoe, thereby providing, in addition to the desirable properties mentioned, clearance spaces between the shoe and wheel which serve to ventilate 60 and keep cool the wearing face of the shoe and to afford means for escape of grit and other foreign particles finding their way between the shoe and wheel.

The object of the second feature of the invention is to provide a safety attachment which is so arranged with respect to the body of the shoe and the attaching lug or other equivalent shoe-fastening device as to prevent the detachment and falling away of portions 70 of the shoe from the brake-head in case of transverse or other fracture thereof, while avoiding weakening the attaching lug or other analogous part.

In the drawings: Figure 1 is a face view of a brake-shoe embodying one feature of my invention. Fig. 2 is a longitudinal section thereof. Fig. 3 is a transverse section taken on line 3—3 of Fig. 1. Figs. 4, 5 and 6 illustrate different arrangements of the chilled 80 areas of the wearing face of the shoe. Figs. 7 and 8 are longitudinal sections of a brake-shoe showing two forms of safety devices for preventing dismemberment of the parts of a fractured brake-shoe. Fig. 9 is a transverse 85 section taken on line 9—9 of Fig. 7. Figs. 10 and 11 are perspective views of the two forms of safety devices shown in Figs. 7 and 8, removed from the shoe.

First referring to the feature of my improvements relating to the wearing or friction face of the shoe, it consists, in general terms, of forming the wearing face of the shoe with a groove or depression of substantial depth, the side and bottom walls of 95 which and the metal adjacent to said walls are chilled a desired distance laterally and outwardly from said walls, thereby producing at the sides and at the bottom of said depression chilled or hardened areas which prolong the life of the shoe against the wearing action of the wheel tread, the soft area or areas of the wearing face being relied upon to produce the desired friction efficiency between the shoe and the wheel. The chilled 105 areas at the sides of said grooves or depressions take the first wear brought upon the face of the shoe, and after the wearing face has been worn down to the bottom of the groove or depression the chilled area at the 110

bottom thereof takes the wearing action due to friction of the wheel tread on the shoe. The depth of the chill is such that it extends towards the back of the shoe such distance 5 that it will be effective so long as it is desirable to use the shoe. Preferably, the chill groove or depression is transversely curved 10 at its bottom, as shown in Fig. 3, thus throwing the chilling lines divergently outward so that the lateral width of the chilled area at 15 the bottom of the groove or depression which is brought into use during the latter part of the life of the shoe is substantially the same as the chilled areas at the sides of the groove or depression, available at the beginning of the use of the shoe. The chilling of the walls of the grooves or depressions is effected in the usual manner by chill bars or plates during the casting operation.

20 Referring now specifically to the shoe in which my invention is shown as embodied in various forms, A designates a shoe of standard form and dimensions, usually made of a gray iron casting, a the curved wearing face 25 of the shoe, and A' designates a familiar form of attaching lug provided with a key-way a' to receive a standard form of key by which the shoe is attached to the brake-head. So far as is concerned the improved 30 wearing face herein claimed, the structural features of the shoe above referred to may be varied as desired.

In Figs. 1, 2 and 3 of the drawing the groove or depression comprises a straight 35 part B disposed longitudinally of the shoe and centrally of the wearing face thereof, and diverging branch portions B', B' at the ends of the wearing face which extends to the lateral margin of said face. In the arrangement shown in Fig. 4, a single continuous groove or depression is provided, which consists principally of a straight longitudinal portion C and laterally and oppositely curved end portions C', C' which extend to the side 45 margins of the wearing face. In the arrangement shown in Figs. 5 and 6, the grooves or depressions D and D', respectively, thereof extend transversely across the wearing face of the shoe from one side 50 margin to the other. In the latter two figures are shown a plurality of grooves or depressions which are arranged parallel to each other. The grooves D of Fig. 5 extend directly across the wearing face or at right 55 angles to the longitudinal axis of the shoe. The grooves or depressions E of Fig. 6 extend obliquely across the wearing face.

The different arrangement of the grooves or depressions herein illustrated are only a 60 few of many practical forms and dispositions which they may be made to assume, while maintaining the general advantages of the chilled areas of the sides and bottoms of the grooves or depressions.

65 It will be noted that in each of the arrange-

ments of the grooves or depressions illustrated a chilled area or areas extend transversely across the wearing face of the shoe from side to side thereof, which is advantageous, inasmuch as it provides a chilled area 70 or areas of uniform hardness from side to side of the wearing face.

Another advantage of carrying the ends of the grooves or depressions entirely to the margins of the wearing face is that such arrangement provides clearance spaces through 75 which grit or other foreign substances finding their way between the brake-shoe and the wheel may escape, and also provides means for ventilating the wearing face of the shoe. 80

Referring now to the second feature of the invention which is illustrated in Figs. 7 to 11, inclusive, and which embraces a safety device which is applied to the shoe in such manner as to hold the parts of a fractured shoe 85 together and prevent them from falling from the brake-head, said improvements consist, in general terms, in providing malleable or other tough metal members which are anchored in the body of the shoe and are provided with loops or retaining members which are external to and so arranged with respect to the retaining lug or member of the shoe 90 that the locking key or other equivalent device which fastens the shoe to the head passes 95 through the loops of the safety members, whereby in case of fracture of parts of the shoe the safety devices become suspending members by which the parts of the shoe are suspended from the brake-head. The said 100 suspending devices are not designed primarily to strengthen the shoe body by reason of being embedded therein, though when so connected with the shoe may incidentally produce such strengthening effect. They 105 may be anchored to the shoe body in other ways.

In the construction shown in Figs. 7, 9 and 10, the devices, which I have herein termed suspended devices, comprise two loops E, E 110 made of malleable rods or wires and embrace parallel side members e, e, connected by a transversely curved portion e' at their outer ends. The said parallel members e, e are shown as embedded in the back of the shoe, 115 as clearly shown in Figs. 7 and 9. The inner ends of said suspending devices are of closed or looped form and are bent upwardly to constitute loops e² which lie against the opposite side faces of the retaining lug A' but are 120 not embedded therein. As a result of this construction, the upturned looped ends e² of the suspending devices receive the locking key by which the shoe is locked to the head, whereby, should the shoe become fractured 125 and the fractured parts separate, or should the lug be broken off from the shoe, said broken part will be suspended from the locking key by the suspending devices. In view of the fact that the upturned looped portions of the 130

suspending members are not embedded in the retaining lug, the lug, which is of relatively small cross-section, retains its full strength and is not weakened by reason of the chilling action of the metal of said suspending devices on the metal which forms the lug. It may be found desirable in practice to provide some means for attaching the free parts of the upturned loops e^2 to the attaching lug so as to prevent said loops from being objectionably bent outwardly from the lug during the handling of the shoe in the shop or during shipment. This may be effected in any suitable manner, as by molding small bodies, a^3 , of metal against the cross members of the loops and the sides of the lug, as shown in Figs. 7, 8 and 9.

By reason of the closed end portions e' of the suspending members E, it will be noted that said members are interlocked with the body of the shoe in a manner to effectively prevent fractured parts of the shoe slipping off the suspending devices, as might be true if the side portions e of said suspending members were made straight.

In Figs. 8 and 11 of the drawings, I have shown another form of suspending device designated by F. Two of these devices are provided, as in the other construction, each consisting of side members f which are connected at their inner ends by upturned looped portions f' , similar to the looped portions e^2 before referred to. At the other or outer ends of the suspending devices the side members f are reversely bent upon themselves to provide members f^2 lying between said side members and generally parallel therewith. This arrangement produces the required interlocking connection of the suspending devices with the shoe-body for the purpose hereinbefore set forth. In the arrangement shown in Figs. 8 and 11, the suspending devices are interlocked with each other in such manner that the suspending loop f' of each member is located at the side of the attaching lug A' remote from that portion of the shoe in which the main body of the suspending device is embedded. This same arrangement may be followed with respect to the form of suspending device shown in Figs. 7, 9 and 10, in which event one of the upturned looped portions e^2 will be made sufficiently large to be received by the correspondingly looped portion of the other device.

I claim as my invention:

1. A brake-shoe, the wearing face of which is formed partially of soft metal and having a depression of substantial depth, the side and bottom walls of which depression are chilled to provide hardened areas on the sides and bottom thereof.

2. A brake-shoe, the wearing face of which is formed with a depression of substantial depth, having a part which extends longitudinally of said face, the side and bottom

walls of said depression being chilled to provide hardened areas at the sides and bottom thereof.

3. A brake-shoe, the wearing face of which is formed partially of soft metal and having a depression of substantial depth extending in part transversely of the wearing face, the side and bottom walls of the depression being chilled to provide hardened areas at the sides and bottom thereof. 75

4. A brake-shoe, the wearing face of which is formed partially of soft metal and having a depression of substantial depth extending from side to side of the wearing face and open at the ends thereof at the side margins of said face, the walls of the depression being chilled to provide hardened areas exterior to the depression. 80

5. A brake-shoe, the wearing face of which is formed with a depression, of which a portion extends longitudinally of the face and a portion extends transversely of said face, the walls of said depressions being chilled to provide hardened areas exterior to said depression. 85

6. A brake-shoe, the wearing face of which is formed with a depression, of which a portion extends longitudinally of the face and a portion extending transversely of said face and opening at the side margins of the face, 90 the side and bottom walls of said depression being chilled to provide hardened areas at the sides and bottom of said depression. 95

7. A brake-shoe, the wearing face of which is formed with a depression of substantial 100 depth, the sides and bottom walls of which are chilled to provide hardened areas on the sides and bottom of the depression, the bottom of said depression being transversely curved. 105

8. The combination with a brake-shoe and its apertured retaining lug, of a pair of malleable wire loop-shaped safety devices anchored to the shoe, the inner ends of said loop being turned upwardly and fitting one against each side of the retaining lug but not embedded therein, the arrangement being such that the side and inner end members of the loop partially inclose the aperture of said lug and constitute suspending members through 110 which is adapted to extend a key which locks the shoe in place. 115

9. The combination with a brake-shoe and its attaching lug, of safety devices anchored to and adapted to hold the parts of the shoe 120 together in case of fracture of the shoe, said devices being provided with loops which rise from the body of the shoe and are located adjacent to the sides of the retaining lug, the loop of each device being located on that side 125 of the lug remote from the part of the shoe to which it is anchored.

10. The combination with a brake-shoe and its retaining lug, of a safety device anchored to the body of the shoe and formed 130

with a loop which fits on the side of the retaining lug, but is not embedded therein, the opening in said loop being so arranged with respect to the retaining lug as to receive 5 a locking device designed to engage the retaining lug to lock the shoe on the brake-head, and means for holding the free ends of said loops fixed to the retaining lug.

In testimony, that I claim the foregoing as my invention I affix my signature in the presence of two witnesses, this 9th day of August, A. D., 1907.

EDWIN S. WOODS.
